DUPLICATING MACHINE

Edward M. Springer, Chicago, Ill., assignor, by mesne assignments, to Heyer Inc., Chicago, Ill., a corporation of New York

Filed May 24, 1957, Ser. No. 661,460

25 Claims. (Cl. 101—232)

The present invention relates to a duplicating machine, and more particularly to an automatic duplicating machine.

More specifically stated, the machine forming the subject matter of the invention is power driven, by means such as an electric motor, and is shut off pursuant to the passage through the machine of the last of a stack of copy sheets placed in the machine for receiving impressions in the duplicating process.

A broad object of the invention is to provide a duplicating machine having novel means for automatically shutting it off in the manner stated.

Another object is to provide a duplicating machine and means for automatically shutting it off, in which the shut-off means is controlled by the copy sheets placed in the machine and is sensitive to the copy sheets including the last of the stack of such copy sheets which, while it is in place on the tray for normally supporting it, retains the control means in a first position, and when it leaves the tray and passes through the machine, it enables the control means to drop through a great distance, whereby to provide highly accurate control in the shutting off operation.

Another object is to provide, in an electrically driven machine, means for shutting off the machine, which includes electromagnetic means that is momentarily energized for performing the shutting off and stopping functions, and mechanical latching means for thereafter holding the machine in shut-off condition, whereby the electromagnetic means may be de-energized, so that the electric current supplied to the machine need not be continued after the machine has been shut off.

A further object is to provide a machine driven by an electric motor, and automatic means for shutting it off, in which the electric motor is de-activated in the operation of shutting off the machine, whereby to eliminate the necessity for clutch means between the electric motor and the parts driven thereby.

Another object is to provide a duplicating machine and means for shutting it off including a brake shoe engageable with a relatively high-speed rotating part, whereby to accurately control the stopping position of the slower moving parts connected in driving relation therewith.

Still another object is to provide a duplicating machine of the character just stated in which, because the brake shoe engages the relatively high-speed part, the moving parts may be permitted a certain degree of overrun in stopping, with consequent reduction in shock as when stopped abruptly, while nevertheless enabling stopping the parts accurately in predetermined position.

A still further object is to provide a duplicating machine driven by power means, such as an electric motor, and means for automatically shutting off and stopping the machine including a brake shoe normally held in braking position when the driving means is de-activated and the machine is shut off, in which the brake shoe can be released, by a simple manual manipulation, whereby the machine can easily be manipulated manually as may

2

be desired for repositioning certain parts, and the machine can be provided with a crank for operating it in the event of a power failure.

Still another object is to provide a duplicating machine with means for automatically shutting it off pursuant to the last of a stack of copy sheets passing through the machine, as referred to above, and novel means for effecting a time delay action so that after the last sheet leaves the supporting tray, the machine will continue a cycle of operation that will enable it to pass entirely through the machine.

A further object is to provide a duplicating machine through which copy sheets pass in a duplicating operation, and the machine makes one cycle for each copy sheet, in which the machine may be adjusted to provide cycles to accommodate copy sheets of different lengths.

Another and more specific object is to provide a duplicating machine having a rotating drum carrying a master for forming impressions on copy sheets fed successively through the machine from a stack placed on a supporting tray, in which means is provided for automatically shutting off the machine pursuant to the last sheet from the stack passing therethrough, and further in which time delay means is provided for enabling the last sheet to pass entirely through before the machine is shut off, wherein novel means is provided for making adjustment for cycling the machine to accommodate copy sheets of different lengths, such for example as 11" and 14" sheets which are commonly used lengths.

30 A further object is to provide a duplicating machine with means for automatically shutting it off pursuant to the last of a stack of copy sheets passing therethrough, as referred to above, in which means is provided for alternatively conditioning the machine to operate through only a single cycle at each operation.

Other objects and advantages of the invention will appear from the following detail description taken in conjunction with the accompanying drawings in which:

Figure 1 is a perspective view of a duplicating machine made according to the present invention, the view being at an angle from the right, front;

Fig. 2 is a perspective view of the duplicating machine from the opposite corner relative to Fig. 1, or the left, rear;

Fig. 3 is a perspective view oriented according to Fig. 1, with the trays for the copy sheets removed;

Fig. 4 is a plan view of the machine with the side casing members removed and certain other elements eliminated;

Fig. 5 is a front elevational view of the machine with the side casing members and certain other elements removed from the machine;

Fig. 6 is a vertical fore-and-aft sectional view taken approximately on the line 6—6 of Fig. 4, but showing portions of the trays for the copy sheets in place;

Fig. 7 is a side elevational view of the machine taken from the right side thereof, with the respective side casing member removed, this view being taken approximately on line 7—7 of Fig. 4;

Fig. 8 is a side elevational view from the left side of the machine, with the respective side casing member removed, the view being taken approximately on the line 8—8 of Fig. 4;

Fig. 8A is a detail view of a portion of the latching means and associated elements shown at the right-hand end of Fig. 8, showing the latching means in latching position;

Fig. 9 is a view taken approximately on the line 9—9 of Fig. 4, with certain portions broken away;

Fig. 10 is a detail view of one of the latch elements used in the latch means of Fig. 9;

Fig. 11 is a detail view of another element utilized in the assembly of Fig. 9;

Fig. 12 is a sectional view showing brake means and certain other elements as viewed at line 12—12 of Fig. 4;

Fig. 13 is a view of certain operating linkage shown in Fig. 8, the linkage being for the most part isolated from its surroundings;

Fig. 14 is a large scale view of certain details at the right-hand portion of Fig. 13;

Fig. 15 is a large scale view of certain details, also of 10 the right-hand portion of Fig. 13;

Fig. 16 is a view similar to Fig. 13, but with certain elements in an alternate position;

Fig. 16A is a fragmentary perspective view showing certain elements of the machine constituting a modified 15 form of the trip means;

Fig. 17 is a detail view of certain elements shown at curved line 17—17 of Fig. 7;

Fig. 18 is a detail view of certain elements shown at the left-hand end of Fig. 7, isolated from surrounding elements;

Fig. 19 is a view similar to Fig. 18, but with certain of the elements in a different position;

Fig. 20 is a view similar to Figs. 18 and 19, but with the elements in still a different relative position;

Fig. 21 is a view similar to Figs. 18 to 20, but with the elements in a different relative position;

Fig. 22 is also a view similar to Figs. 18 to 21 showing the elements in still a different relative position; and

Fig. 23 is a diagrammatic view showing the electric circuit employed and certain other elements associated with the circuit.

Referring now in detail to the drawings, a duplicating machine made according to the present invention is shown in its entirety in Figs. 1 and 2, and is shown in Fig. 3 with the trays for the copy sheets removed.

In the following description of the structural details of the duplicating machine reference is made to prior co-pending applications disclosing and claiming certain subject matter in common with the present machine and reference is made to those applications for the purpose of minimizing herein detailed description of those portions of the structure of the present machine that are also included in the prior applications. The two applications mentioned are Serial No. 420,232, filed April 1, 1954, now Patent No. 2,830,534, in the name of the present inventor and Francis K. Moore, and Serial No. 623,492, filed November 20, 1956, in the name of the present inventor. For the purpose of facilitating reference to the machine, and the parts thereof, the view of Fig. 1 may be considered as taken at an angle from the right, front, the machine having a front end 12, a rear end 14, a right side 16 and a left side 18. The general operation of the machine, as will be understood, is that a stack of copy sheets 20 are placed on a tray 22 at the front end of the machine and are fed through the machine and after the duplicating process has been performed, they emerge from the machine, at the rear and are stacked on a tray 24 at that end.

Attention is directed particularly to Figs. 4, 5 and 6 for the main frame structure and the principal parts of the machine that are common with the duplicating machine of the above-mentioned co-pending applications. The machine includes a frame structure which consists essentially of a base 26 and upstanding side plates 28 and 30 at the right and left hand sides, respectively, of the machine. The side plates 28 and 30 support certain main operating parts of the machine between them, and other parts such as drive elements and certain control elements on the exterior surfaces thereof. The plates are provided, in the finished machine, with side casing members 32 and 34, respectively, to enclose certain of the parts mounted on the exterior of the side plates, to provide a finished appearance, as will be understood. These side casing members 32 and 34 are omitted from Figs. 4 and

5, as well as other figures, to expose the normally enclosed elements to view.

Referring now to Figs. 4, 5 and 6, a rotatable drum 36 is mounted on and between the side plates, adjacent the top thereof and thus adjacent the top of the machine, and has a clamp bar 38 for clamping the leading edge of a master to be carried by the drum. In Fig. 6 the drum 36 is shown in position with the clamp bar 38 adjacent the top, but as will be brought out in detail hereinafter, the drum will at times stop at a position with the clamp bar 38 in an alternate position, namely, adjacent that shown in dot-dash lines displaced angularly from the full line position and removed from the top of the machine. Co-operating with the drum 36 is an impression roll 40 arranged for biasing movement toward the drum for gripping or firmly engaging a copy sheet 20 passing through the machine in the duplicating process, this sheet passing between the drum and the impression roll. The impression roll 40 is not a driven roll, but it rotates in response to its engagement with the copy sheet passing between itself and the drum 36. The copy sheets 20 are fed to the drum 36 and impression roll 40 by a pair of rolls including a moistening roll 42 and a presser roll 44. The moistening roll 42 is a driven roll, being driven by means to be described hereinbelow, while the roll 44 is an idler roll, being rotated by its engagement with the copy sheet passing between that roll and the moistening roll 42.

The impression roll 40 and presser roll 44 are mounted in hangers 46 which are arranged to pivot about eccentric axes on supporting elements such as studs 48. A tensioning device 50 is utilized for regulating the pressure exerted by the rolls 40 and 44 on the respective counterpart elements. The mounting for these rolls and the tensioning device are fully described in the above-mentioned co-pending applications.

The moistening roll 42 is coated with a fluid by means of a wick bearing on the roll and extending into a transverse trough (not shown) supported by the side plates. The fluid is provided to the trough by means of a fluid tank 56 which is mounted on and extends between the side plates 28 and 30 and is rotatable between two positions for alternately supplying fluid to the trough and removing the tank from feeding relation with the trough. The tank may be rotated by a suitable handle and grip 54 (Fig. 5). The trough has a receptacle 58 (Figs. 4, 5, and 7) extending to the exterior of the associated side plate 28 and the tank 56 is provided with valve means 60 for controlling the flow of fluid from the tank to the receptacle 58. The tank is movable to an inoperative position as shown in Fig. 7 in which the valve means 60 is removed from the receptacle 58 and is closed, and to an operative position in which the valve means extends into the receptacle 58 and is opened. The tank and related means for feeding fluid to the moistening roll 42 are fully described in the first of the two above-mentioned applications and need not be described further in detail herein. It will be noted from Figs. 5, 6, and 7 that the tank 56 is mounted adjacent the top of the side plates 28 and 30 and it is also closely adjacent the drum 36, as will be understood from the desired compact arrangement of the elements, to minimize the over-all dimensions of the machine. As mentioned above, the drum 36 in certain instances will stop at the end of an operating cycle with the clamp bar 38 adjacent the position shown in dot-dash lines in Fig. 6. In this position it is accessible to the user only with difficulty because of the close proximity of the fluid tank 56, and in order to facilitate clamping and unclamping of the master in the clamp bar 38 it is desired that the clamp bar be positioned in an upper position on the drum, and accessible to the operator. The means for accomplishing this result will be described in detail hereinbelow.

In Fig. 6 the tray 22 at the front end of the machine on which the copy sheets are placed, is shown. This

tray is preferably removable and for the most part is shown in detail in the above-mentioned applications. It includes a deck element 62, a front downturned flange 64 and side downturned flanges 66. The tray is supported in position by means of pins 68 on a fixed element in the machine, projected through holes in the front flange 64, and clips 70 on the side plates providing upwardly facing openings for receiving the side flanges 66. The tray may be removed by lifting up on the outer end to release the side flanges 66 from the clips 70 and then withdrawing forwardly on the tray to release the front flange 64 from the pins 68.

The stack of copy sheets 20 is placed on the tray and fed from the stack by a feed means indicated in its entirety at 72 and described in detail hereinbelow. At the present point suffice it to say that that feed means includes feed wheels 74 which are rotated at the appropriate portion of the cycle of operation for feeding the sheets from the tray. These feed wheels are preferably of rubber or rubber-like material and engage the top-most sheet of the stack when the feed means 72 is resting thereon, as is done in the operation of the machine, being gravity actuated. Upon rotation of the feed wheels 74 the uppermost sheet from the stack is forced rearwardly (to the right, Fig. 6) and engages one or another of inclined baffles 76 which deflects the leading edge of the sheet through the passage 78 therebetween and into engagement with the rolls 42 and 44. Feeding of the sheet from that point on in the cycle of operation is believed obvious, and is explained in detail in the above-mentioned applications. Upon the duplicating process being completed, and the sheets leaving the drum 36 they are deposited on the tray 24, a stacking device 80 of conventional nature being employed to aid in the stacking.

The deck element 62 of the tray 22 is provided with depressions 82 (Fig. 6), one for each of the feed wheels 74. These depressions are of minimum dimensions relative to the feed wheels, namely, they are arcuate in one direction with a radius substantially equal to that of the wheels, and of a width only slightly greater than the width of the wheels. In the operation of the device the copy sheets 20 on the tray support the feed means 72 and this support is provided even by the last single copy sheet remaining on the tray, the dimensions of the depressions 82 being no greater than necessary to accomplish this purpose. In Fig. 6 is shown a single copy sheet 20 remaining on the tray, and supporting the feed means 72. Upon this last copy sheet 20 leaving the tray, and passing through the machine, the feed wheels 74 drop into the depressions 82 and by reason of the movement effected by this drop certain control functions are performed for stopping the machine. These functions will be brought out in detail hereinbelow.

The details of the structure of the feed means 72 are best seen in Figs. 1, 3, 5, 6, 7, and 8. The feed means 72 includes a rotatable shaft 84 on which the feed wheels 74 are mounted for rotation therewith, the shaft being supported by arms 86 and 88 on the right and left-hand sides, respectively, of the machine (see Figs. 7 and 8). The feed means also includes a bar 90 above the shaft 84 and mounted in the side arms 86 and 88 and forming with the shaft and arms a relatively rigid device that may be grasped by the hand for manipulating it. This assemblage with the side arms 86 and 88 making up the feed means 72 is swingable about the axis of the studs 92 and 94 on which the arms are pivoted, being urged downwardly by gravity and thus arranged to follow the stack of copy sheets 20 and thereby forming a sensing device for controlling the means for automatically shutting off the machine when the stack of copy sheets is depleted, and the last one has passed through the machine. The studs 92 and 94 are suitably mounted in the respective side plates of the frame. Preferably a spring such as the hairpin spring 96 (Fig. 7) is arranged

for biasing upwardly on the arm 86 and thus on the feed means to minimize or take up the play in the rack. The side plates 28 and 30 are provided with arcuate slots 98 (Fig. 7) and 100, (Fig. 6), respectively, for receiving the shaft 84 and bar 90 of the rack. If desired the slots 98 and 100 may be dimensioned for serving as a limit stop for defining the extent to which the feed device 72 may lower, but it is also within the scope of the invention to provide that the downward movement of the feed device is limited by the floor of the depressions 82 (Fig. 6) when engaged by the feed wheels 74. The drop of the feed wheels 74 from the last copy sheet 20 over the depressions, into the depressions, is relatively great and therefore considerable latitude is provided whereby the slots 98 and 100 may be relied on for defining the lower limit to which the feed device 72 may move and still efficiently perform the shutting off function.

The drive for the duplicating machine is derived from 20 a suitable source such as an electric motor 102 (Figs. 5 and 6) mounted at a convenient location and preferably adjacent the front. It is partially enclosed by a cover or shield 104 (Figs. 3 and 6) which is generally L-shaped having a vertical leg or panel 106 at the front and a top horizontal leg or panel 108. The motor 102 may be of any desired type and is provided with a drive shaft 110 which is connected by means of a suitable coupler 112 with another shaft 114 which extends through an opening 116 (Fig. 7) to the exterior where 25 a drive pulley 118 is mounted thereon. The coupler 112 serves as a permanent connection between the drive shaft 110 and the shaft 114, and it is pointed out that the machine made according to the present invention does not require a clutch between the motor and the parts 30 driven thereby; there is no disconnection in the drive in the operation of stopping the machine. In stopping the machine, the rotor of the motor 102 remains connected with the shafts 110 and 114 and is stopped in the same operation of stopping the remaining driven parts of the 35 machine. A belt 120 (Fig. 7) is trained over the pulley 118 and another and larger pulley 122 mounted for rotation by suitable means on the side plate 28 as by a stud 124. Provided on or connected to the large pulley 122 is a small pulley 126 over which a belt 128 is trained, this belt also being trained over another pulley 130 40 mounted on the shaft 132 on which the drum 36 (Fig. 6) is mounted. It will be seen that the arrangement and relative dimensions of the pulleys referred to establish a greatly reduced speed drive between the shaft 114 and 45 the drum. Mounted on the outer end of the drum shaft 132, on the right-hand side, is a hand wheel 134 (Figs. 1, 3, and 5). The drum 36 is mounted on the shaft 132 for adjustment angularly with respect to the shaft, which is done by means of thumb wheels 136 (Figs. 1 and 3) 50 in the manner described in the first of the above-mentioned co-pending applications. The wheel 134 in the present case replaces the crank utilized in the above-mentioned applications in view of the fact that the present device is power driven and automatically controlled. However, it may be that the user will desire to 55 adjust the drum 36 manually, for a purpose referred to below, and in that event he may merely grip the wheel 134 and turn it. Consequently, the wheel 134 is of substantial size to facilitate grasping it and turning 60 the drum. It is within the compass of the present invention to provide a handle or crank means on the wheel 134 to operate the machine manually, if such should be desired as in the case of power failure. Notwithstanding 65 the automatic control of the machine, the machine can be 70 readily adapted to manual operation.

The means for feeding the copy sheets from the tray 22 through the machine is driven by the drum 36, or more particularly the shaft 132. The specific drive utilized for the feeding means is substantially the same as 75 that disclosed in the second of the above-mentioned co-

pending applications and hence reference thereto in the present instance will be minimized. Attention is directed particularly to Figs. 4 and 8 in which the drum shaft 132 is projected through the left-hand side plate 30, and on the end of the shaft outwardly of the side plate are mounted a pair of timing discs 138 and 140 and a gear 142 arranged in a rigid assembly for rotation in unison with the shaft 132. The gear 142 is in mesh with a gear 144 forming one of a pair of gears fixed for conjoint rotation, the other of which 146 is coaxial therewith and in mesh with a gear 148 included in a compound clutch means 150. This clutch means includes control elements controlled respectively by the timing discs 138 and 140 in certain predetermined relation with respect to a cycle of operation of the machine. Drive is established from the clutch means 150 to the shaft 84 through a series of gears 152, 154, 156, and 158. The first of these gears, namely, 152, is mounted on the stud 94 on which the arm 88 is mounted (Fig. 8) and the gears 154 and 146 are mounted on the arm 88 and movable therewith, while the gear 158 is mounted on the shaft 84, and, of course, on the arm 88 for movement therewith. The clutch means 150 and gear 148 are mounted on a shaft or stud 160 coaxial with the shaft on which the moistening roll 42 (Fig. 6) is mounted, and upon rotation of a certain element of the clutch means 150, rotation of the roll 42 is accomplished.

It might be stated also that the feed wheels 74 and moistening roll 42 are freewheeling, i.e., each is operative for feeding the copy sheets the necessary extent for engagement by the next succeeding feeding device. For example the feed wheels 74 rotate through such portion of a cycle of operation as is necessary to feed a copy sheet from the stack on the tray 22 to the moistening roll 42 and presser roll 44. Thereafter drive to the feed wheels 74 ceases and the copy sheet on being drawn through the machine turns the feed wheels 74, the structure including an overrunning clutch to effect such operation. Similarly, the moistening roll 42 is rotated after the leading edge of the copy sheet engages it, sufficient to move the copy sheet therewith and the leading edge of it into engagement with the drum 36. Thereafter the driving means to the moistening roll 42 ceases and the roll then becomes freewheeling, a clutch means being provided to accomplish that purpose, and rotates in response to the copy sheet being drawn therewith. The copy sheet is finally fed out of the machine and onto the tray 24 by the drum 36 in conjunction with the impression roll 40.

Other elements shown in Fig. 8 and not entering into the present invention, but which are described in one or both of the above-mentioned co-pending applications include a counter 162, a mounting bracket 164 for the tank 56, a latch means 166 for controlling the clutch means 150, and a pulley 168 mounted on a shaft for controlling the tensioning means 50 (Fig. 6), the pulley being associated with a flexible cord 170, the ends of which are secured to a bar 172 mounted for swinging movement and having a handle 174 (Figs. 3 and 6) extending through a slot 176 in the associated side plate 30 for convenient access to the operator.

Attention is next directed to a unit or assemblage indicated in its entirety at 178 shown at the lower right-hand corner of each of Figs. 4 and 5 and shown in greater detail in Figs. 9 to 12. This unit or assemblage is a switching-braking-latching device or structure and constitutes one of the main subassemblies or portions of the automatic drive and control of the machine. This unit or assemblage is associated with the shaft 114 for performing a braking operation on that shaft. The braking operation is accomplished by a solenoid and the same solenoid is incorporated in relay means which includes an operating switch (or brake-stop switch) indicated at 180 which may be a conventional switch, preferably a microswitch. This switch is a simple on-off switch (see

also Fig. 23) and is mounted in any convenient location such as on the base 26 of the framework. The switch has a control arm 182 arranged for movement in a horizontal plane and is self-biased to closed position, or the full line position of Fig. 23. This position is also that shown in dotted lines in Fig. 4, and that when moved toward the observer as viewed in Fig. 5. The switch is open when in the opposite position, namely, the full line position of Fig. 4 and moved away from the observer in Fig. 5. The switch is moved to open position by a solenoid to be described hereinbelow. The unit or assemblage 178 includes a frame structure 184 which includes side plates 186 spaced apart along the shaft 114 and provided with suitable bearing means 188 to support the shaft. The side plates 186 have lower turned over portions 190 secured to the base 26 and are interconnected at one or more places by suitable ties such as a rod 192. The frame structure including the side plates and tie 192 thus provide a rigid structure for supporting the brake shoe and latch means as well as other elements to be described hereinbelow.

The shaft 114 is provided with a brake drum 194 disposed between the side plates 186, in the form of a collar or large diameter ring on the shaft. The unit or assemblage 178 includes a brake shoe 196 for braking engagement with the brake drum 194 on the shaft (see particularly Figs. 5, 9, and 12). The brake shoe 196 may be of conventional form, having an asbestos type brake lining engaging the drum 194, and being mounted on a hanger 198. The hanger 198 may be generally U-shape, having side arms or flanges 200 and an interconnecting web 202. The specific mounting for the brake shoe may take the form of a pin 204 secured to the brake shoe and slidably mounted in a hole in the web 202, a compression spring 206 being interposed between the shoe and web for biasing the shoe away from the web and in the direction of the brake drum 194. Upon application of the brake, the compression spring 206 yields against the force of moving the hanger 198 in brake applying direction in the usual manner. The hanger 198 is pivotally mounted on the tie rod 192, at the upper end of the hanger, and the lower end of the hanger is connected by means of a cross pin 208 to a link 210 (Fig. 9) which in turn is connected to the armature 212 of a solenoid 214. The solenoid is mounted on the base 26 at a convenient location and upon energization of the solenoid the armature 212 is retracted (moved to the right, Fig. 9), which consequently swings the lower end of the hanger 198 to the right or counter-clockwise (Figs. 9 and 12), bringing the brake shoe 196 into braking engagement with the brake drum 194.

This same operation in applying the brake also actuates the switch 180, and specifically moves the switch to open position, swinging the control arm 182 thereof in counter-clockwise direction (Fig. 4) or away from the observer (Fig. 5). This actuation of the switch control arm 182 is accomplished through the medium of a switch trip arm 216 located as shown in Figs. 4 and 5 and shown in detail in Fig. 11. This arm is pivoted on the tie rod 192, and hence is coaxial with the brake hanger 198, having an aperture 218 for so pivotally mounting it. The arm also has a notch 220 for receiving a pin or stud 222 mounted on the brake hanger 198 (Figs. 5 and 12). A tension spring 224 is interconnected between the lower end of this arm and a fixed element such as a bracket 226 (Figs. 5 and 9) mounted on the base 26. The spring 224 biases the arm 216 clockwise (Fig. 9) or toward the observer (Fig. 5) or in other words in direction to enable the switch control arm 182 to assume its closed position. The switch trip arm 216 is moved in the opposite direction, or in direction to trip the switch control arm 182, by the brake hanger 198, as stated, and it is accomplished specifically through the pin or stud 222, i.e., upon movement of the brake and the hanger 198 in brake applying

direction, the switch trip arm 216 is moved thereby in direction for tripping the switch control arm 182.

Latching means are provided for latching the brake in braking position and latching the switch 180 in open position, both positions being such as moved by the solenoid. This latching means is in the form of a pair of identically shaped arms or elements 228 and 230, located as indicated in Figs. 4 and 5 and shown in detail in Fig. 10. Each element includes a pin or stud 232 by which it is pivotally mounted on the respective side plate 186. The arm has a lower horizontal extension 234 having notches 236 and 238 therein as well as an upstanding projection 240 serving as a stop means outwardly of the notches, as will be brought out in detail hereinbelow, and finally an aperture 242 adjacent the outer end or toe 243 of the lower portion. The arm or element also includes an upstanding portion 244 at the top of which is an arcuate slot 246 for receiving a pin 248 (Fig. 9) mounted in the respective side plate 186 for guiding the arm 228 in its latching and unlatching movements. At the upper end of the vertical portion 244 is a horizontal extension 250 having an upstanding extremity defining a surface 252 for engagement by a bar 254 (Figs. 5 and 9) in the unlatching operation. A tension spring 255 is interconnected between the toe 243, as in the aperture 242, and a fixed portion such as the tie rod 192 for biasing the arm in latching direction which is clockwise direction as viewed in Figs. 9 and 10.

As mentioned above, the latching elements or arms 228 and 230 are utilized for latching the brake in applied or braking position and the switch 180 in open position pursuant to those elements being moved to their respective positions by the solenoid 214. Referring first to the means for latching the brake, attention is directed to Figs. 4, 5 and 9 which show a pin 256 on the brake hanger 198 adjacent the lower end of the latter, extending to the right (Figs. 4 and 5) into engaging relation with the associated latch element or plate 228. This pin or stud is positioned for engaging in one or the other of the notches 236, 238 (Figs. 9, 10, and 12). When the brake is in applied or braking position the pin 256 is received in the notch 236 (Fig. 12) but when the brake is in released or non-braking position, namely, that of Fig. 9, the pin 256 is received in the notch 238. The tension spring 255 serves to bias the latching element or arm 228 in clockwise direction to retain the pin 256 in the respective notch 236 or 238. The upstanding projection 240 serves to prevent the brake hanger 198 from swinging too far in clockwise direction or brake releasing direction.

The latching operation for latching the switch 180 in open position is similar to that described above in connection with the latching operation with respect to the brake. The stud 222 on the brake hanger 198 extends laterally therefrom and into engagement in the notch 220 in the switch trip arm (Figs. 11 and 12). Upon the brake being moved to braking position (counterclockwise, Figs. 9 and 12) the pin or stud 222 engaging in the notch 220 moves the switch trip arm 216 in the same direction. The switch trip arm 216 is provided adjacent its lower end with a pin or stud 258 extending laterally into engaging relation with the associated latching element or arm 230 (to the left as viewed in Figs. 4 and 5). This pin or stud 258 is arranged for entering into the notches 236, 238 (Fig. 12) in the associated latch arm 230 precisely in the same manner as described above in connection with the latching of the brake. The latch element or arm 230 is biased in latching direction (clockwise, Fig. 9) by the associated tension spring 255.

In the shutting off and stopping operation, it is assumed that the brake is reposing in non-braking position (Fig. 9) and the switch 180 is closed, or released by the switch trip arm 216; with the elements in such condition, the solenoid 214 (Fig. 9) is caused to be energized, which draws on the brake hanger 198 and moves

the latter to braking position (Fig. 12); this movement of the brake hanger, through the pin 222 engaging in the notch 220, draws the switch trip arm 216 in the same direction; the switch trip arm engages the switch control arm 182 and moves it in similar direction to switch-open position. The brake hanger and switch trip arm are then latched by the latch elements or arms 228, 230, in the manner described above.

The latch elements or arms 228, 230 are unlatched, in the normal functioning of the machine through the medium of the bar 254 which is mounted on and actuated by a starter arm or control lever indicated in its entirety at 260 and described in detail hereinbelow in connection with the next phase of the operation of the machine. The starter arm is provided with a push button 262 which is exposed to the exterior as shown in Figs. 1 and 3 for easy access by the operator. Suffice it to say at the present point, that upon depression of the push button 262, the starter arm 260 is rotated in clockwise direction (Fig. 7) which moves the bar 254 to the left as viewed in Fig. 9 or toward the observer as viewed in Fig. 5. This bar then engages the surfaces 252 of the latch elements or arms 228, 230 and rocks the latter in counterclockwise direction (Fig. 9) which lowers the lowermost horizontal arm portions 234 and releases the pins 256, 258 from the respective notches 236. The tension spring 224 (Figs. 5 and 9) moves the trip switch arm 216 in releasing direction (to the left, Fig. 9, toward the observer, Fig. 5). The switch trip arm 216 through the medium of the pin 222 which engages in the notch 220 moves the brake hanger 198 in the same direction, namely, in the non-braking or releasing direction. The starter arm or push button 262 is actuated normally only momentarily, and then released. This momentary actuation is sufficient to enable the brake hanger and switch trip arm to be moved in releasing direction, after which and pursuant to release of the push button 262 the latch elements or arms 228, 230 are drawn upwardly by the respective tension springs 255 so that the pins 256 and 258 become engaged in the respective notches 238.

The above operation in which the latching means for both the brake and the switch 180 are released is normally that accomplished in the usual operation of the machine in which the machine is put into operation after having been previously automatically stopped, as explained in detail hereinbelow. In other words, the brake remains in braking position and the switch 180 in open position while the machine is at rest, but when both the brake and switch latching means are moved to released position it is intended that the machine be put into operation. However, it is desired at times that the brake means be released without releasing the latching means for the switch. This is accomplished through a manual control means indicated in its entirety at 264 in Fig. 9. This latch means includes a push button 266 exposed through the front panel 106 (Fig. 3) of the shield 104. This latch means may be of any suitable construction and includes a bottom horizontally extending trip element 268 positioned for engaging the toe 243 of the lowermost extremity of the latch arm 228 for the brake (Figs. 4 and 9). The push button may include an element 270 vertically slidably in mounts 272 fixed to the panel 106. A tension spring 274 is interconnected between the upper mount 272 and the trip element 268, normally retaining the push button 266 in raised position but upon depression of the button, as by engaging it with the thumb (Fig. 3) and moving it downwardly, the element 268 engages the toe 243 and moves the latch arm in counterclockwise or releasing direction (Fig. 9). The brake means is thus released, but the arrangement between the pin 222 and slot 220 is such as to enable movement of the brake hanger relative to the switch trip arm which remains in latched position. The brake hanger readily moves in clockwise or releasing direction in this unlatching operation due to gravity, as will be readily observed in Figs.

9 and 12, but if desired spring means for this purpose may be utilized. In a later operation of starting the machine when the push button 262 on the control lever 260 is depressed, the bar 254 merely performs the unlatching operation on the latch element 230 for the switch.

The operating sequence of the braking and latching functions will be referred to again hereinbelow in connection with other functions of the machine in the general operation.

Attention is next directed to the starter arm or control lever 260 referred to above and other parts directly related thereto. Attention for this purpose is directed particularly to Figs. 5, 7, and 17 to 22 inclusive. The starter arm is disposed at the right side of the machine adjacent the front, with the push button 262 exposed to the exterior at the right front, as mentioned above, and as shown clearly in Figs. 1 and 3. This starter arm performs certain operating functions in connection with the feed device 72 through the medium of the arm 86 (Fig. 7), and with a start switch 276. The starter arm 260 includes an arm or lever proper 278 which may be generally plate-like in form and is pivoted intermediate its ends on a pin or stud 280 mounted on the adjacent side plate 28. Adjacent the lower end of the lever or arm 278 is a slot 282 guidingly receiving a pin 284 fixed on the side plate 28. The starter arm 260 is biased in counterclockwise direction (Fig. 7) to an outer position by suitable means such as a wire spring 286 having a central portion coiled on the pin 280 and its ends engaging the push button 262 and the pin 284, respectively. On the lever or arm 278 adjacent the lower end of the latter is another stud 288 positioned for engaging the control arm 290 of the switch 276. Also adjacent the lower end of the arm 278 and fixed thereon is another pin 292 (see particularly Figs. 17 to 22, inclusive) which preferably has a roller thereon and which is disposed for certain engaging cooperation with an extension 294 of the arm 86, the details of which are brought out hereinbelow. The bar 254, referred to above, is secured to the lower end of the arm 278, and extends through the opening 116 (Fig. 7) of the side plate 28.

Upon actuation of the starter arm or control lever 260 as by depression of the push button 262 and consequent rotation thereof in clockwise direction, (Fig. 7), the pin or stud 288 engages the switch control arm 290 of the switch 276 and swings the latter in counterclockwise direction. This switch is indicated diagrammatically in Fig. 23 and is normally biased to a first position shown in full lines in Fig. 23 and with the switch control arm 290 (Fig. 7) moved in clockwise direction. Upon movement of the switch control arm 290 in the opposite direction by actuation of the push button 262 as explained above, the switch 276 is moved to its other closed position shown in dotted lines in Fig. 23. The switch 276 may be of standard construction and the details need not be described herein.

The extension 294 on the arm 86 (Figs. 7 and 17 to 22, inclusive) may be a separate piece secured to the arm 86 or an extension integral therewith. This extension includes a main portion 296 extending downwardly and arcuately about the axis of the stud 92 on which the arm 86 is pivoted. Mounted on the lower end of the main portion 296 is an arm 298, arranged for swinging movement on a pivot element 300 such as a pin fixed on the lower end of the portion 296. This arm as shown in Fig. 7 is arcuate, following the curvature of the main portion 296 itself, and as shown in Fig. 17 is made up of an outer element 302 and an inner element 304. The outer element 302 is provided with inwardly extending studs 306 on which the inner element 304 is mounted. The inner element 304 is shorter than the outer element and disposed adjacent the upper or swinging end of the latter and has at its upper end a camming surface 308 facing generally inwardly toward the main portion 296,

and a downwardly facing and surface 309 disposed for engaging the pin 292.

The arm 298 is biased to a normal position (clockwise, Fig. 7) by a tension spring 310 anchored between the arm and a fixed pin on the main portion 296. A stop pin 312 is mounted on the main portion 296 and is engaged by the arm 298 for limiting movement of the latter in clockwise direction or to its normal position as moved by the spring 310.

The pin 292 on the lever arm 278 extends laterally into engaging relation with the arm extension 294; as seen most clearly in Fig. 17 it extends laterally beyond the main portion 296 which may be plate-like in shape. It then extends toward the arm 298, beyond the inner element 304 but short of the outer element 302. When the arm 86 is in its uppermost position (i.e., when the feed device 72 is in its uppermost position), the inner element 304 clears or moves upwardly beyond the pin 292 and the latter is enabled to move under the element 304, the element of the main portion 296 serving as a stop for the pin 292, the lever arm being biased in that direction by the spring 286. The pin 292 in such position under the lower end edge 309 of the element 304 thus serves as the means for normally retaining the arm 86, and thereby the feed device 72 in its uppermost position, except in single-cycling operation, as explained below. Upon release of the pin from such holding position, the feed device 72 is enabled to lower, and this is in consequence of the operation of starting the machine which is done by depression of the push button 262 which in turn rotates the starter arm or control lever 260 in clockwise direction for moving the pin 292 from under the element 304.

A condition such as that just described in connection with starting the machine is represented in Fig. 19 where the starter arm 260 is shown in position as rotated in clockwise direction pursuant to depression of the push button 262. In such position, the pin 292 is removed from below the element 304. The feed device 72 is then enabled to drop or lower, and the limit of its lowering movement is determined, in normal operation, by the thickness of the stack of copy sheets 20 on the tray 22 (Fig. 1). The machine continues normal operation until the copy sheets are all removed from the tray and is shut off under the control exercised by the feed device 72 pursuant to its movement to its lowermost position. This position is that in which the feed wheels 74 enter into the depressions 82 (Fig. 6) as explained above. Fig. 20 illustrates the condition at an intermediate point, for example when the stack of copy sheets is approximately half depleted. The lowering movement of the feed device 72 and consequent lowering movement of the arm 86 and extension 294 (Fig. 7) continues to the position represented at Fig. 21 in which the arm 298 has passed the pin 292, and the pin 292 is thereby disposed above the arm 298. The starter arm 260 is then free to be moved in counterclockwise direction by the spring 286, and upon such movement, the pin 292 enters into a recess 314 above the arm, and engages the main portion 296 which serves as a limit stop for the pin and consequently of the starter arm as mentioned above. When this position is reached, the machine is stopped as explained hereinbelow, and in order to condition the machine for further normal operation the feed device 72 and hence arm 86 (Fig. 7) is raised. This is done merely by grasping the rod 90 (Fig. 5) and lifting it. This operation causes relative vertical movement between the extension 294 and the pin 292, as it will be understood the latter is fixed against vertical movement. This relative movement brings the camming surface 308 on the arm element 304 into engagement with the pin 292 and cams the arm 298 outwardly (counterclockwise, Fig. 22) and enables the arm 86 to be raised. After the latter is raised a sufficient extent, the arm 298 is swung inwardly (clockwise) until it reaches its home

position in engagement with the pin 312, and in this position the pin 292 is disposed under the lower end 309 of the inner element 304 of the arm, as explained above. This pin then serves to retain the feed device 72 in its raised position until the machine is again started in operation by depression of the push button 62. The pivoted arm 298 enables raising the feed device 72 without actuating the starting bar 262 and consequent recyclicing the machine.

The phase just preceding describes control of the stopping operation with particular reference to the matter of sensing the copy sheets on the tray and the last of them leaving the tray and being fed into the machine. Attention is next directed to that phase of the machine and its operation whereby the machine is automatically stopped after the last copy sheet has passed entirely through the machine. It will be appreciated that after the last copy sheet has left the tray, the machine should not be stopped until that copy sheet has passed entirely through the machine. For this purpose the drum which carries the master for imprinting on the copy sheets, or drive means closely associated with the drum, is utilized for completing the automatic stopping operation, and therefore, a dual control is exercised by the feed means 72 and drum 36. Attention is now directed particularly to Figs. 8 and 13 to 16, inclusive.

Figs. 13 and 16 shows certain linkage indicated in its entirety at 316 generally isolated from the surrounding structure. This linkage also is shown in Fig. 8 in its relation to the other adjacent operating parts of the machine, and is mounted on the left-hand side plate 30 on the outer side thereof and covered by the respective side casing member in the completely assembled machine. This linkage extends substantially across the side plate from front to rear and has elements for sensing the drum and elements engagingly related to the feed means 72.

Referring to the individual elements making up the linkage, they include a central arm or link 318 pivoted at 320 on the side plate 30 and having arms 322 and 324 bent at an angle to each other to form a bell crank lever. Forwardly of the link 318 is an arm or link 328 pivoted intermediate its ends on the side plate 30 by suitable means such as a stud 330. The arm or link 328 is pivoted at 332 at one end to the arm 324 and at its other end at 334 to a star arm 336. The star arm 336 is pivoted on a stud 338 on the side plate 30 and has a depending extension or arm portion 340 disposed for actuation of a cut-off switch 342. The switch 342 is a standard switch, and preferably is a microswitch similar to the switches 180 and 276. This switch has a normal self-biased position shown in full lines in Fig. 23, and a second closed position shown in dotted lines in Fig. 23 to which it is moved by the star arm 336. The two positions of the star arm 336 are shown in full and dot-dash lines, respectively, in Figs. 13 to 16. In the full line position of the star arm the switch control arm 344 is in raised position and the switch is then in the full line position represented in Fig. 23. When the star arm 336 is moved to the dot-dash line position, the switch control arm 344 is depressed and the switch is moved to the dotted line position of Fig. 23.

Forwardly of the star arm 336 and cooperating therewith is a linkage control arm 346 secured to or formed as an integral extension of the arm 88 (Fig. 8) which supports one end of the shaft 84 and bar 90 of the feed means 72. This control arm 346 is raised and lowered in the raising and lowering movements of the feed means 72. It is rigid with the arm 88 and arcuate about the axis of the stud 94 on which the arm 88 is pivoted. The arm 346 is provided with a camming or working surface 348 having a central high portion 350 and a low portion 352 at its lower extended end, as well as a low portion 354 at its upper end. The star arm 336 includes an extension or arm portion 356 provided with a roller 358 engageable with and riding on the camming surface 348.

The roller engages the various portions 350, 352, and 354 of the arm depending upon the position of the arm, vertically, in the operation of the machine as brought out in detail hereinbelow. At this point it may be stated briefly that when the roller 358 engages the portion 350, the star arm 336 is in a position approximating the dot-dash line position (Fig. 13) while, on the other hand, when it engages either the portion 352 or 354, the star arm 336 assumes its full line position.

Connected with the opposite or rear end of the link of lever 318 is a stop yoke 360 having a relatively straight shank portion 362 with arms 364 and 366 branching off in the shape of a Y at one end of the shank portion. At the end of the shank portion opposite the arms is a slot 368 slidably receiving a pin on an arm 372. The arm 364 is provided with a pin 374 which extends through a slot 376 in the side plate 30, and the arm 366 has a pin 378 extending through a slot 380 in the side plate. The yoke 360 is pivotally connected to the arm 322 of the link 318 as by a pin 382. The yoke 360 is supported entirely by its two connections with the link 318 and arm 372, being free of mounting on the side plate 30.

The arm 372 is in the form of a bell crank lever, pivoted on a pin 384 secured on the side plate 30. The bell crank lever 372 has two arms, 386 and 388, the former having the pin 370, above referred to, at its extended end, and the latter having a pin 390 forming the means for pivotal connection between the arm 388 and another link 392. The latter link is pivoted at its opposite end on a pin 394 on a bell crank lever 396, the other end of which is pivoted on a pin 398 on a slide 400. The slide 400 is mounted directly on the side plate 30 by means of studs 402 mounted on the side plate and riding in slots 404 in the slide. The slide includes an angle portion having a downturned flange 406 in which the slots 404 are formed and a top horizontal flange 408 on which is mounted a button 410 exposed through the side casing member, as shown clearly in Figs. 1, 2, and 3. This slide 400 has sliding movements on the pins 402 between the extreme positions shown in Figs. 13 and 16, respectively, for setting the machine for stopping the drum at either of two different positions described in detail hereinbelow, and referred to as an "11 inch" and a "14 inch" position. The bell crank lever 396 is pivotally mounted on a stud 412 secured to the side plate 30, and is operative, in response to sliding movements of the slide 400, for actuating the remainder of the linkage.

For the purpose of performing a tripping operation in the actuation of the linkage 316, the drum 36 is provided with a camming or trip element 414 arranged for engaging one or the other of the pins 374, 378, in certain predetermined positions of the drum and phases of operation of the machine for effecting stopping of the machine. The element 414 may be mounted on the end surface of the drum (Fig. 4) and the pins 374, 378 extend through the side plate so as to be positioned for engagement by the trip element. The orbit of the outermost point of the camming or trip element 414 is indicated by the circle 416, and this element engages either the pin 374 or 378 depending on which is disposed within the orbit, it being possible for only one of the pins to be so disposed, the positioning of the pins being mutually exclusive. The positioning of these pins is accomplished by the slide 400, and assuming a first position such as shown in Fig. 13, the linkage is disposed with the pin 374 in that orbit. The shifting or changing of position is accomplished by shifting the yoke 360 which is accomplished by sliding the slide 400 to the opposite position, or that shown in Fig. 16. This sliding movement rocks the bell crank lever 396 in counterclockwise direction, and this bell crank lever acting through the link 392 rotates the arm or bell crank lever 372 also in counterclockwise direction. Rotation of the latter, acting through the pin 370, rotates the yoke 360

in counterclockwise direction about the axis of the pin 382 carried by the link 318. This rotation or rocking of the yoke 360 removes the pin 374 from the orbit 416 and moves the pin 378 into the orbit.

For the purpose of following through the operating movements of the linkage 316, a single position of the yoke 360 is assumed, namely, that shown in Fig. 13. In this position of the slide 400 and related elements of the linkage, the pin 374 is in position to be engaged by the camming or trip element 414 on the drum. Assuming operation of the machine and consequent rotation of the drum 36, when the drum rotates (counterclockwise) to the position approaching that in Fig. 13, the camming or trip element 414 approaches the pin 374. Continued rotation of the drum causes the element to engage the pin 374 and the latter normally is within the orbit of the outer extremity of the camming or trip element, and the latter, having a curved camming surface for the purpose, cams the pin 374 outwardly. The yoke 360 is held against swinging movement by the two point connection at the pins 382 and 370, and the effect of the camming action of the element 414 on the pin 374 is to move the yoke 360 translationally outwardly, i.e., in radial direction. This movement is indicated by the dotted line position illustrated in Fig. 13. The yoke 360 slides relative to the pin 370, and the connection at the pin 382 between the yoke and the bell crank lever 318 causes the latter to be rocked or rotated in counterclockwise direction, also to the dot-dash line indicated. This rotation of the bell crank lever 318 in counterclockwise direction rotates the link or lever 328 in clockwise direction, and the latter rotates the start arm 336 in counterclockwise direction, in each instance the respective member being moved from the full line position to the dot-dash line position. The actuation of the linkage in the manner just described presupposes the position of the linkage control arm 346 in either its uppermost position of Figs. 13 and 14, or its lowermost position as shown in Fig. 15. Assuming first the uppermost position of the arm as shown in Figs. 13 and 14, the roller 358 on the star arm is in register with the low point 352 on the arm, enabling the star arm and the other elements of the linkage to assume their full line position. In this full line position, the pin 374 is within the orbit of the trip element 414. The action of tripping the pin 374 rotates the various elements of the linkage in the manner mentioned, in which the roller 358 is lifted from the control arm 346. After the tripping operation, the linkage returns to its full line position in which the roller 358 again engages the control arm at the low point 352.

A similar situation exists in the case where the arm 346 is in its lowermost position, as shown in Fig. 15, the low point 354 being essentially in the same arc with the low point 352. The roller 358 thus engages and is lifted off of the low point 354 in precisely the manner described in connection with the low point 352. The actuation of the linkage in either case causes the switch 342 to be actuated, through the medium of the control arm 344, and causes stopping of the machine as will be explained in detail hereinbelow, the action being directly related to the then assumed position of certain other operating elements of the machine.

During the normal operation of the machine between the starting operation and the stopping operation, it is desired that the linkage 316 and the switch 346 not be constantly actuated in each rotation of the drum, and for this purpose the control arm 346 is provided, the arm acting through the high portion 350 for this purpose. In the normal operation of the machine and when the feed means 72 is lowered from its uppermost position, as explained above, the linkage control arm 346 is lowered a corresponding amount. This brings the high point 350 into register with the roller 358 on the star arm 336. The throw between the low point and the high point is such that the linkage is moved from the full

line position to the dot-dash line position, and preferably slightly more, which action withdraws the pin 374 out of the orbit of the trip element 414. This arrangement retains the linkage in inoperative position so that during the operation of the machine the pin 374 is not tripped at each revolution of the drum, as would be the case were it not for the high point 350. When the stack of copy sheets from the tray 22 is depleted, and the feed means 72 is lowered to its lowermost extent, the arm 346 is also lowered to its lowermost position which places the low point 354 in register with the roller 356 on the star arm 336. This enables the linkage to assume its full line position with the pin 374 in the orbit of the element 414, and the latter in its normal revolution on the drum engages the pin and trips the linkage which in turn actuates the switch and shuts off the machine in conjunction with other elements according to the setting of the latter.

The tripping of the linkage by the element 414 is accomplished at a predetermined point in the rotation of the drum, as will be understood. The setting illustrated in Fig. 13 is for example a "14 inch" setting to accommodate copy sheets of 14" length, which is one of two popular lengths commonly used in duplicating machines, the other being 11". The "11 inch" setting is illustrated in Fig. 16 where the pin 378 is illustrated as being within the orbit of the trip element 414, as explained above. In the setting of the linkage, as illustrated in Fig. 16, the linkage is actuated and the switch 342 is actuated in accordance with the position of the pin 378 relative to the angular position of the drum. This position is angularly offset with respect to the pin 374 and, consequently, the machine is stopped at a different position in the rotation of the drum. More specifically, when the setting is as shown in Fig. 13, or a 14" setting, the drum is stopped in the position shown in Figs. 4 and 6, with the clamp bar 38 disposed adjacent the top, as indicated in full lines. On the other hand, with the setting as represented in Fig. 16, or an 11" setting, the machine stops with the drum positioned with the clamp bar as indicated in dot-dash lines in Fig. 6.

In either case the machine is brought to a stop according to the control established by the drum and in this way it is not stopped until the last copy sheet leaving the tray 22 passes entirely through the machine and leaves the drum after an imprinting or duplicating operation. Further reference to this feature is made hereinbelow.

The invention also includes a modified control arrangement for stopping the machine pursuant to a copy sheet passing entirely through the machine. This modified arrangement finds particular utility in view of the "raise and lower" feature referred to above. The raise and lower feature has to do with positioning the imprinted material on the copy sheet at relatively higher or lower positions thereon. This control is exercised by adjusting the drum angularly relative to the shaft on which it is mounted. The means for feeding the copy sheets through the machine is driven by the shaft on which the drum is mounted, e.g., by means of the gear 142 which is mounted on the disc assembly 138, 140. If the drum is adjusted angularly relative to the shaft a great amount, a position may be reached in which a copy sheet of 14" length may not be moved entirely past the drum at the time the machine is stopped pursuant to tripping the stop means by the 14" setting of the stop yoke 360. This phenomenon is due to the fact that the copy sheets are driven through the machine by a drive means which can assume different rotational positions relative to the drum.

In order to overcome such a situation the modification of Fig. 16A may be utilized. The construction illustrated in this figure includes the side plate 30, discs 138 and 140, gear 142 and stop yoke 360, all in the construction described above. The present construction also includes the pin 378 on the stop yoke 360 which projects through

the slot 376 in the side plate 30. The pin 378 is that utilized in the "11 inch" setting.

The present modified construction includes a trip arm 415 mounted on the stop yoke 360 by suitable means such as by welding. This trip arm extends into the space between the discs 138 and 140 in position to be tripped by a trip element 417 secured to one of the discs, such as 140. The length and direction of the arm 415 are such, relative to the pin 378, as to serve for the 14" trip operation. The trip element 417 is so disposed on the disc 140 that when the stop yoke 360 is moved to the 14" setting, the element 417 engages the arm 415 and trips the linkage 316 (Figs. 13 and 16) after a 14" copy sheet passes entirely through the machine and past the drum regardless of the "raise and lower" setting of the drum. The trip element 417 being secured to the disc 140 trips the arm 415 at a predetermined position of the feed means for feeding the copy sheet, and is not affected by the setting of the drum relative to the drive means. In the present instance, the stop yoke 360 does not have an 11" trip element (such as the pin 374).

Provision is made for "single cycling" of the machine, i.e., the machine will operate through one cycle in response to its being turned on and will then automatically be shut off. The use of the machine in such manner will find particular use in connection with so-called systems work, in which the copy sheets, because of the nature of the work, are fed through the machine manually. In such case the machine is turned on and it operates through one cycle, during which one copy sheet is manually fed to and passes through the machine. This single cycling control is effected through the medium of the feed means 72 and attention is directed particularly to Figs. 8 and 8A. It will be recalled that in the normal operation of the machine in which it is to cycle repeatedly, the feed means 72 is lowered into engagement with the stack of copy sheets. In the single cycling operation, the feed device 72 is retained in raised position by means of a latch device indicated in its entirety at 416, which is utilized for latching the arm 88 in raised position. This latching device 416 includes an arm 418 (see also Fig. 4) having angle arm portions, one of which 420, is pivoted on the side plate 30 as at 422 by means of a pin mounted on the side plate, and the other, 424, on which is mounted a push button 426 exposed through the adjacent side casing member as shown in Figs. 1 and 3. This latching arm 418 is an over-center device having a slot 428 receiving a pin 430 mounted on the side plate 30 and serving as a limit stop in both directions of angular movement of the plate. A tension spring 432 is anchored between the upper swinging end of the arm 418 and a pin 434 on the side plate 30. Upon swinging movement in clockwise direction (Figs. 8 and 8A) in response to manipulation of the push button 426, a toe 435 on the lower end of the arm engages under a shoulder 436 on the arm 346. In such position of the latching means the arm 88 and thus the feed means 72 is retained in raised position, and in such position the machine operates through only a single cycle after which it automatically shuts off, as explained more fully hereinbelow. When the operator wishes the machine to operate continuously he throws the latching means 416 in the opposite direction, namely, to the position shown in Fig. 8, in response to which the toe 434 is removed from the shoulder 436 and the arm 88 and consequently the feed means 72 is permitted to lower pursuant to other manipulation during operation of the machine as described below. The latching device 416 is releasably retained in either of its two extreme positions by means of the spring 432.

Reference may now be made to the manner of operation of the machine in normal use. For this purpose assume a position of rest in which the machine normally is disposed between periods of operation. In such position the push button 262 is biased outwardly (to the left

in Figs. 1 and 7). In this position also the brake 196 in Figs. 9 and 12 is held in braking position by the latch arm 228. The switch 180 (Fig. 5) is latched in open position (Fig. 23) by the latch member 230 (Fig. 9). The switch 342 on the left-hand side of the machine (Fig. 8) is in the full line position of Fig. 23. The switch 276 on the right-hand side of the machine (Fig. 7) is in the full line position of Fig. 23. The feed device 72 is in raised position (Fig. 3) being held in such position by the pin 292 (Fig. 18). Also, the single cycling latch means of Figs. 8 and 8A is in a position shown in Fig. 8, i.e., non-latching position.

With the machine set according to the foregoing, the operator places a stack of copy sheets 20 on the tray 22 (Fig. 1) and aligns them in proper position. Assume that the copy sheets so placed in the machine are of 11" length. The operator then moves the slide 400 to the 11" position (Fig. 16) if it was not at that time in such position. The operator then depresses the push button 262 (Fig. 1) which will rock the starter arm (Fig. 7) in clockwise direction. This movement of the arm 260 performs several functions, as follows: through the medium of the bar 254 (Figs. 5 and 9) the latch members 228, 230, are moved to unlatching position. One of the latch members, 228, on being unlatched, releases the brake (Figs. 9 and 12) from braking position. The other of the latch members, 230, on being unlatched, releases the switch control arm 182 on the switch 180 (Fig. 5) and the switch moves to the full line position of Fig. 23. The pin 292 is removed from the element 304, and the feed means 72 is permitted to drop, with the feed wheels 74 dropping into engagement with the copy sheets. The movement of the starter arm or control lever 260, in the manner mentioned, furthermore actuates the switch control lever 290 (Fig. 7) and actuates the switch 276 to the dotted line position of Fig. 23. In this connection attention is directed to Fig. 23 which shows certain mechanical elements in purely diagrammatic arrangement to show their association and function in the control of the circuit. These mechanical elements include the starter arm 260 which, when actuated, through the medium of the pin 288, moves the switch 276 to the dotted line position, and through the medium of the bar 254 releases the latch members 228 and 230.

Pursuant to the foregoing manipulations, namely, depression of the push button 262, the machine is placed in operation according to the following. Referring to Fig. 23, a current source is indicated at 438, from which current passes through conductor 440, switch 276 which at this time is in the dotted line position, through the conductors 441 and 448, and then to the motor 102 and through the conductor 450, completing the circuit. The motor is thus placed in operation and the machine is operated in the usual manner. The drum 36 is rotated through the drive shown in Fig. 7, namely, pulley 118, belt 120, pulley 122, pulley 126, belt 128, and pulley 130 which is secured to the drum shaft 132. Thereupon the rotation of the drum and the drive to the moistening roll 42 (Fig. 6), feed wheels 74 and impression roll 40, are precisely as described in the second of the two above-mentioned co-pending applications.

The operation of the machine continues as just referred to until the last of the copy sheets 20 is removed from the tray 22. The copy sheets are removed from the tray by the action of the feed wheels 74, these wheels and the feed means 72 on which the wheels are mounted constituting a device for sensing the copy sheets on the tray for automatically shutting off the machine when the sheets are depleted. As mentioned above, this action is accomplished pursuant to the wheels 74 falling into depressions 82 (Fig. 6). When this happens, two things occur which condition the circuit of Fig. 23 so that the machine will be automatically shut off at the

end of a cycle as determined by the rotation of the drum 36.

The first occurrence is that the starter arm 260 is returned to its initial position, i.e., the position shown in Fig. 21 which is equivalent to that of Fig. 7. In explanation, it will be recalled that on depression of the push button, the starter arm (Fig. 19) was removed from under the element 304, whereupon the arm 86 with the elements 296 and 302 mounted thereon moved downwardly. The pin 292 then engaged against the outer peripheral edge of the element 304 and the latter retained the starter arm in its actuated or depressed position, i.e., the position of Fig. 19, with the switch 276 in the dotted line position of Fig. 23, until the arm 86 reaches its lowermost position pursuant to depletion of the copy sheets, whereupon the pin 292 is enabled to enter into recess 314 (Fig. 21) pursuant to which the starter arm 260 moved in counterclockwise direction to its initial position. In the latter movement, the switch control arm 290 (Fig. 7) was released and the switch 276 assumes the full line position of Fig. 23.

The second occurrence in response to the feed means 72 reaching its lowermost position is related to the control means and linkage illustrated in Figs. 13 to 16. When the control arm 346 reaches its lowermost position pursuant to the feed device 72 reaching that position, the roller 356 on the star arm 336 is permitted to drop into the low point or notch 354 as represented by the full line position illustrated most clearly in Fig. 15. This enables the linkage to assume its full line position at all points from the roller 358 to the forked end of the yoke 360. This position places the pin 374 within the orbit of the trip element 414. When the latter engages the pin 374 pursuant to completion of the respective revolution of the drum, it trips the pin 374 and consequently actuates the linkage, moving the star arm to its dot-dash line position, and the latter depressing the switch control arm 344 on the switch 342. The latter actuation moves the switch from the full line position to the dotted line position of Fig. 23.

The movement of the two switches, namely, 276 and 342, at the times and under circumstances referred to, automatically stops the machine. The condition of the circuit of Fig. 23 under such condition is as follows: the switch 276 is in the full line position (Fig. 23); and the circuit leads from the source 438 through the conductor 440, switch 276, conductor 442, switch 180, conductor 444, and with the switch 342 in its dotted line position as so actuated by the linkage 316 as just described, the current continues through that switch and conductor 452 to solenoid 214 referred to above and shown in Fig. 23; the circuit is completed through conductor 454 and conductor 450 to the source 438. Upon energization of the solenoid 214 the switch 180 is moved to its dotted line position and the brake 196 is applied, as described above. The latch means 228 and 230 then become effective for latching the switch and brake in the positions to which they were just moved. It will be understood that the movement of the switch 276 from the dotted line position to the full line position of Fig. 23 in the shutting off operation only momentarily breaks the circuit to the motor, and as a practical matter the motor continues running.

It will be realized that the solenoid 214 remains energized only momentarily because upon energization of the solenoid the switch 180 is opened and the current to the solenoid is cut off. Thus, when the switch is opened, the solenoid becomes de-energized, but the switch is latched in its open position and the brake is latched in braking position by the latch means 228 and 230, which constitute mechanical means for the purpose. Thus is provided a means for electrically actuating the switch and brake but utilizing a mechanical means for retaining them in their actuated position, enabling the electrical means, or solenoid, to be immediately de-energized.

It will be appreciated that the star arm 336 (Figs. 13 and 23) is actuated also only momentarily so that the switch 342 is moved to its dotted line position (Fig. 23) only momentarily and it immediately returns to the full line position, whereupon the circuit can be readily conditioned for operation (from switch 276 and through conductors 441 and 448) in response to depression of the push button 262.

The purpose of moving the linkage 316 (Figs. 13 to 16) to the dotted line position by means of the arm 346 is to eliminate repeated actuation of the linkage before it is intended that the machine be brought to a stop. It will be understood that actuation of the switch 342 in an intermediate position of the arm 346 would not shut off the machine since the switch 276 remains in the dotted line position of Fig. 23, and movement of the switch 342 with the circuit in such condition, would be idle movement. Hence, the means for presenting repeated and needless actuation of the linkage 316.

Upon shutting off the machine pursuant to depletion of the copy sheets, as just described, the machine remains at rest with the feed means 72 in its lower position. To condition the machine for further use, the operator grasps the bar 90 (Figs. 1, 3, and 5) and raises it. It is normally retained in such position by the pin 292.

Whenever the operator wishes, if it should be desired, to shut off the machine manually and before it would shut off automatically, he merely raises the feed means 72 from the stack of copy sheets to its uppermost position.

This operation conditions the machine the same as if it reaches its lowermost position—the pin 292 is enabled to pass under the element 304, releasing the starter arm and enabling the switch 276 to assume the full line position of Fig. 23; and the low point 352 on the arm 346 registers with the roller 358, enabling the pin 274 to be projected into the orbit of the trip element 414.

In the single cycle operation of the device, the push button 426 (Figs. 8 and 8A) is pushed downwardly to the position shown in Fig. 3. This movement rocks the arm 418 to move the toe 434 under the shoulder 436 and this retains the feed means 72 in raised position. Thereupon in an operation of the machine the push button 262 is depressed. This sets up the circuit as described in connection with the operation of the machine above, but the condition is maintained only through one cycle of operation, i.e., one revolution of the drum. When the feed device 72 is retained in its raised position by the latch means of Fig. 8A, and when the control button or push button 262 is depressed, the pin 292 (Fig. 19) while it is removed from under the lower end 309 of the element 304, the arm 86 is retained in upper position and when the push button 262 is released the pin 292 is then enabled to move under the element 304 and the starter arm 262 to assume its normal position, namely, that of Figs. 7 and 18. Upon depression of the push button 262 and rocking of the lever 260, the pin 288 (Figs. 7 and 23) moves the switch 276 to the dotted line position of Fig. 23. The circuit is then conditioned as described above in the beginning of the operation, namely, current from the source 438 passes through the conductor 440, the switch 276, conductor 441, conductor 448, the motor 102 and returns through the conductor 450 to the source. However, the button is depressed only momentarily and released and when it is released, the switch 276 moves to the full line position of Fig. 23 and the circuit through the motor is then from the source 438, conductor 440, switch 276, conductor 442, switch 180 which is closed, conductor 444, switch 342 which is in the full line position, conductor 446, conductor 448, motor 102 and conductor 450, and in return to the source. The circuit then remains conditioned as shown in full lines in Fig. 23. Upon completion of a single cycle, namely, a single revolution of the drum, the trip element 414 engages the pin 374 and actuates the linkage which in turn actuates the star arm 336 and moves the switch 342 to the dotted line position of Fig. 23. The machine

is then automatically shut off and braked in the manner described above in connection with the automatic shut-off when the pin 292 is enabled to drop into the recess 314 as shown in Fig. 21. In each case the switch 276 is in that condition shown in full lines in Fig. 23. It will be recalled from the description above that the low point 352 at the lower end of the arm 346, as shown most clearly in Fig. 14, enables the linkage to assume its full line position. This position of the linkage enables the pin 374 to fall within the orbit of the trip element 414.

The diameter of the drum 36 is such as to accommodate a master, and copy sheets, of a certain predetermined maximum length in accordance with popular demands in connection with duplicating machines. For example, duplicating operations are performed quite often on sheets of fourteen inch length. Although it is desired to accommodate copy sheets of such length, the majority of duplicating work is done on shorter sheets, namely, eleven inch sheets. It is highly desirable that a single machine be capable of accommodating duplicating processes in connection with both of these sizes of sheets with greatest and maximum convenience to the operator. The automatic shut-off and braking operation are initiated by means which senses the copy sheets, but it is desirable that the last copy sheet be permitted to pass entirely through the machine before the machine is entirely shut off. The drum rotates once during each cycle and it is desired that the means for clamping the master, namely, the clamp bar 38 (Fig. 6) be positioned for easy access when the machine comes to rest. This is preferably adjacent the top as shown in Fig. 6 so that the operator can have easy access thereto with a minimum of hindrance from other portions of the machine, such as the tank 56. For this reason the machine is set at an eleven inch position when eleven inch copy sheets are being used. The pin 374 (Fig. 13) is positioned at such angular position of the drum that when the trip element 414 engages the pin, when the pin is in operative position, the machine is brought to a stop with the clamping bar 38 adjacent the top. At this position the copy sheet being imprinted upon in that cycle will have passed entirely through the machine and left the drum and moved onto the tray 24 at the rear of the machine.

On the other hand, when fourteen inch sheets are being used, it is desired that a cycle of operation of the machine be such that the copy sheet being imprinted upon in that particular cycle be passed entirely through the machine, but in order for this to be accomplished, it is necessary for the drum to be rotated a greater amount, or to a position represented approximately by the dot-dash line position of the clamping bar 38 in Fig. 6. Such position of the drum represents a greater portion of a revolution of the drum, and such as to enable the fourteen inch sheet to entirely move past the drum. However, to change a fourteen inch master on the drum would entail considerable difficulty with the clamp bar 38 positioned as shown in dot-dash lines in Fig. 6. When it is desired to so change a fourteen inch master, the operator pushes down on the button 266 (Figs. 1 and 3) which unlatches the latch member 228 (Figs. 5 and 9) and releases the brake, whereupon the operator is enabled to rotate the drum by grasping the hand wheel 134. The operator then rotates the drum to position the clamp bar 38 adjacent the top as indicated in full lines at 6. Thus means is provided for automatically braking the machine in the stopping operation, but convenient means is provided for releasing the brake without putting any of the other operating functions into effect, to enable the machine to be manually rotated. In the use of fourteen inch sheets, the slide 400 is moved to the fourteen inch position, as described above.

It is thought that the invention and many of its attendant advantages will be understood from the foregoing description, and it will be apparent that various changes may be made in the form, construction and ar-

angement of the parts without departing from the spirit and scope of the invention or sacrificing all of its material advantages, the form hereinbefore described being merely a preferred embodiment thereof.

5 I claim:

1. A duplicating machine comprising a support for copy sheets, a rotatable drum for carrying a master for imprinting on the copy sheets, means for feeding copy sheets successively from the support through the machine, means including an electric motor for driving the feeding means and drum through a succession of cycles, the drum making one revolution in a cycle, circuit means for controlling the electric motor, a gravity operated follower arranged for riding on a stack of the copy sheets on the support, and means for automatically stopping the machine including switch means in said circuit means and a manually actuated control member for operating said switch means, the follower and control member having cooperating interengagement whereby in either the uppermost or lowermost position of the follower the control member assumes a retracted position, and when the follower is in its uppermost position and the control member is in its retracted position the control member retains the follower in uppermost position, said switch means having a self-biased position when the control member is in retracted position in which it de-energizes the circuit for stopping the motor.
2. A duplicating machine comprising a support for copy sheets, a rotatable drum for carrying a master for imprinting on the copy sheets, means for feeding copy sheets successively from the support through the machine, means including an electric motor for driving the feeding means and drum through a succession of cycles, the drum making one revolution in a cycle, circuit means for controlling the electric motor, switch means having a first and a second position for controlling the circuit means, a manually actuated control member having a retracted position and an advanced position in which the switch means is in said second position, a gravity actuated follower engageable with copy sheets on the support, the follower being arranged for controlling the control member and enabling the latter to assume its said retracted position when the follower is in either uppermost or lowermost position, manually actuated means for releasably retaining the follower in uppermost position, and means controlled by the drum effective for stopping the machine when the switch means is in its said first position.
3. A duplicating machine comprising a support for copy sheets, a rotatable drum for carrying a master for imprinting on the copy sheets, means for feeding copy sheets from the support to the drum and through the machine, a motor for driving the drum and feeding means, drive means including speed reducing means between the motor and drum for driving the latter and related parts, the drive means including a high speed element between the motor and speed reducing means of a diameter greatly less than that of the drum and rotatable at a speed greatly in excess of that of the drum, means for shutting off the motor, means for braking the drive means including a brake shoe engageable with said high speed element of the drive means, and control means for controlling the shutting off and braking means.
4. A duplicating machine comprising a support for copy sheets, a rotatable drum for carrying a master for imprinting on the copy sheets, means for feeding copy sheets from the support to the drum and through the machine, a motor driving the drum and feeding means, means for stopping the machine in response to the last of the copy sheets leaving the support and passing through the machine including means for shutting off the motor and means for braking the moving parts, said shutting off means and braking means being movable into and out of an operative position, first latch means for retaining the shutting off means in operative position, second latch means for retaining the braking means in operative

position and manually actuatable means for releasing the second latch means to enable manual moving of the drum and related moving parts.

5. A duplicating machine comprising a support for copy sheets, a rotatable drum for carrying a master for imprinting on the copy sheets, means for feeding copy sheets from the support to the drum and through the machine, a motor for driving the drum and feeding means, means for stopping the machine in response to the last of the copy sheets leaving the support and passing through the machine including means for shutting off the motor and means for braking the moving parts, said shutting off means and braking means being movable into and out of an operative position, electromagnetic means for moving the braking means to operative position, the braking means being operative in its own movement to operative position for moving the shutting off means to operative position, first latch means for retaining the shutting off means in operative position, second latch means for retaining the braking means in operative position, and manually actuatable means for releasing the second latch means independently of the first latch means to enable manual moving of the drum and related moving parts.

6. A duplicating machine comprising a support for copy sheets, means for feeding the copy sheets from the support through the machine, means for imprinting on the copy sheets as they pass through the machine, an electric motor for driving the feeding and imprinting means, a circuit for controlling the motor, a switch in said circuit, brake means for braking the machine, means sensing copy sheets on the support and responsive to the last copy sheet leaving the support for actuating the switch and thereby conditioning the circuit for stopping the motor and for applying the brake means, latch means for retaining the switch in the condition thus actuated and the brake means applied, a start switch in the circuit, a starting bar adapted for manual depression and thereby operative for releasing the latch means and actuating the start switch for conditioning the circuit for starting the motor, and additional means for manually releasing the brake means.

7. A duplicating machine comprising a support for copy sheets, means for feeding copy sheets successively from the support through the machine, means for imprinting on the copy sheets passing through the machine, an electric motor for driving the feeding and imprinting means, a circuit for controlling the motor, a cut-off switch in the circuit having a normal first position and a second position, a solenoid controlled by the cut-off switch, an operating switch in the circuit having a normally closed position and being opened by the solenoid when the latter is energized, a start switch in the circuit and having a normal first position and a second position, means controlled by the driven parts of the machine for moving the cut-off switch to its second position at a predetermined point in a cycle of operation of the machine and thereby energizing said solenoid and opening the operating switch and disconnecting the motor, latch means operative for holding the operating switch in open position, a starter arm operative on depression thereof for releasing the latch means and enabling the operating switch to close and also for moving the start switch to its second position and thereby starting the motor.

8. A duplicating machine comprising a support for copy sheets, means for feeding copy sheets successively from the support through the machine, means for imprinting on the copy sheets passing through the machine, an electric motor for driving the feeding and imprinting means, a circuit for controlling the motor, a first switch in the circuit having a normally biased first position and a second position, a solenoid controlled by the first switch, a second switch in the circuit having a normally biased closed position and being opened by the solenoid when the latter is energized, brake means normally in a non-braking position and moved by the solenoid when energized to position braking the driven parts, a third switch

in the circuit and having a normally biased first position and a second position, means controlled by the driven parts of the machine for moving the first switch to its second position at a predetermined point in a cycle of operation of the machine and thereby energizing said solenoid and opening the second switch and disconnecting the motor, and also applying the brake means, latch means operative for holding the second switch in open position and the brake means in applied position, a starter arm operative on depression thereof for releasing the latch means and enabling the second switch to close and the brake means to move to a non-braking position, and also for moving the third switch to its second position and thereby starting the motor.

15. 9. A duplicating machine comprising means for supporting a stack of copy sheets adjacent a front end of the machine, means for feeding the copy sheets successively from said supporting means through the machine in rearward direction, a rotatable drum adjacent the rear end for carrying a master for imprinting on the copy sheets, an electric motor, drive transmitting means for driving the feeding means and drum from the electric motor, and means for automatically stopping the machine in response to the last copy sheet from the stack on the supporting means passing through the machine including a follower sensitive to the stack of sheets on the supporting means and switch means controlled thereby when the last copy sheet leaves the supporting means, cut-off switch means, means interconnecting the drive transmitting means and cut-off switch means for actuating the latter by the drive transmitting means in a position of the drum corresponding to a position of a copy sheet posterior to the drum, and means controlled by the follower for selectively rendering said interconnecting means effective or ineffective.

10. A duplicating machine comprising means for supporting a stack of copy sheets adjacent a front end of the machine, means for feeding the copy sheets successively from said supporting means through the machine in rearward direction, a rotatable drum adjacent the rear end for carrying a master for imprinting on the copy sheets, an electric motor, drive transmitting means for driving the feeding means and drum from the electric motor, means for adjusting the drum relative to the feeding means with respect to timing of a copy sheet, and means for automatically stopping the machine in response to the last copy sheet from the stack on the supporting means passing through the machine including a follower sensitive to the stack of sheets on the supporting means and switch means controlled thereby when the last copy sheet leaves the supporting means, cut-off switch means, means for actuating the cut-off switch means, and means for selectively placing the actuating means in position for actuation selectively by the drum or drive transmitting means, and consequent stopping of the machine at a position corresponding to a position of a copy sheet posterior to the drum, trip means on the drum and drive transmitting means for actuating the switch actuating means at respectively different positions with respect to passage of a copy sheet through the machine, and means controlled by the follower for selectively rendering the actuating means effective or ineffective.

11. A duplicating machine comprising means for supporting a stack of copy sheets adjacent a front end of the machine, means for feeding the copy sheets successively from said supporting means through the machine in rearward direction, a rotatable drum adjacent the rear end for carrying a master for imprinting on the copy sheets, an electric motor for driving the feeding means and drum, start switch means, a follower sensitive to the stack of copy sheets on the supporting means and operative for effecting a movement of said start switch means to motor stopping position in response to the last copy sheet leaving the support, cut-off switch means, means controlled by the drum operative for moving said cut-off

switch means to motor-stopping position at a point in the rotation of the drum corresponding to a copy sheet in position posterior to the drum, and circuit means including the motor and said switch means, said circuit means being operative, when both said switch means are in motor stopping position, for stopping the motor.

12. The combination set out in claim 11 including means controlled by said follower for disabling said means controlled by the drum and thereby preventing said cut-off switch means from being moved to motor-stopping position in certain predetermined positions of the follower.

13. The combination set out in claim 11 including means controlled by said follower for disabling said means controlled by the drum and thereby preventing said cut-off switch means from being moved to motor-stopping position in certain intermediate position of the follower between lowermost and uppermost positions thereof.

14. The combination set out in claim 11 including means controlled by said follower for disabling said means controlled by the drum and thereby preventing said cut-off switch means from being moved to motor-stopping position in certain predetermined positions above lowermost position and enabling the said means to function as stated in the lowermost position, said follower being held by the last single copy sheet of the stack at a position above lowermost position a substantial distance relative to incremental descent due to removal of a single copy sheet.

15. A duplicating machine comprising means for supporting a stack of copy sheets adjacent a front end of the machine, means for feeding the copy sheets successively from said supporting means through the machine in rearward direction, a rotatable drum adjacent the rear end for carrying a master for imprinting on the copy sheets, a motor for driving the feeding means and drum, start control means, a follower sensitive to the stack of copy sheets on the supporting means and operative for effecting movement of said start control means to motor-stopping position in response to the last copy sheet leaving the support, cut-off control means, means controlled by the drum operative for moving said cut-off control means to motor-stopping position at a point in the rotation of the drum corresponding to a copy sheet in position posterior to the drum, and means interconnecting said motor and start and cut-off control means and operative for stopping the motor when both said control means are in motor-stopping position.

16. The combination set out in claim 15 in which said means controlled by the drum includes a trip element on the drum and a plurality of elements actuatable by the trip element and selectively positionable for actuation by the trip element at respective positions angularly about the axis of rotation of the drum said means controlled by the drum being effective for moving said cut-off control means to motor-stopping position at corresponding different angular positions of the drum.

17. The combination set out in claim 11 in which the means for controlling said cut-off switch means includes a trip element on the drum and a plurality of elements actuated by the trip element and selectively positionable for actuation by the trip element at respective positions angularly about the axis of rotation of the drum and effective for moving said switch means to motor-stopping position at corresponding different angular positions of the drum.

18. A duplicating machine comprising a support for copy sheets, a rotatable drum for carrying a master for imprinting on the copy sheets, means for feeding copy sheets successively from the support through the machine, a motor for driving the feeding means and drum through a succession of cycles, the drum making one revolution in a single cycle, start control means for the motor having a normal self-biased first position, and a second position

and capable of effecting operation of the motor in the second position, a manually actuatable member operative for moving the control means to its second position, a follower having an uppermost position and mounted for movement into and out of engagement with copy sheets on said support, and being movable downwardly in response to the stack of sheets becoming depleted, the follower when in such engagement being operative for retaining the manually actuatable lever in position corresponding to the second position of the control means and when in its uppermost and lowermost positions enabling the lever and control means to return to their respective first positions, means for releasably retaining the follower in its uppermost position, and control means operated by the drum in a position of rotation of the latter corresponding to a position of a copy sheet rearwardly beyond the drum operative for stopping the motor in response to the start control means being in its said first position.

19. A duplicating machine comprising a support for copy sheets, a rotatable drum, means for feeding copy sheets from the support to the drum and through the machine beyond the drum, a motor having a rotor for driving the drum and feeding means, permanent drive means from the rotor to the drum for driving the latter and related parts, means for shutting off the motor and braking the drive means, and means for automatically stopping the machine including a follower riding on the copy sheets and descending by gravity, first control means, said follower being operative, on reaching its lowermost position pursuant to the last of the copy sheets leaving said support, for actuating said first control means and placing it in a controlling condition, second control means, and means responsive to rotation of the drum operative, when the first control means is in said controlling condition, for actuating said second control means and thereby stopping the machine after the last copy sheet has passed through the machine to a position beyond the drum.

20. A duplicating machine comprising a support for copy sheets, means for feeding sheets successively from the support through the machine, a rotatable drum for carrying a master for imprinting on the copy sheets passing through the machine, the feeding means including a gravity actuated pivoted follower adapted for engaging the copy sheets on the support, an electric motor for driving the drum and feeding means, a circuit for controlling the motor, a first and a third switch in said circuit, each switch having a normal first position and a second position, means controlled by the drum for moving the first switch to its second position, a starter arm having a normal position and operative in such position for retaining said follower in raised position, and being operative on being depressed for releasing the follower and moving the third switch to its second position, said follower on being released from its uppermost position and descending therefrom being operative for retaining the third switch in its second position and when in its lowermost position enabling the starter arm to return and the third switch to assume its first position, the switches when in their first positions being in series with the motor and movement of the first switch to its second position stopping the motor, said third switch when in its second position establishing a circuit to the motor.

21. The combination set out in claim 20 in which means is operatively connected between the follower and said means controlled by the drum whereby the latter means is rendered operative in either uppermost or lowermost position of the follower and inoperative when the follower is in any intermediate position.

22. The combination set out in claim 21 including manually actuated means for releasably retaining the follower in uppermost position.

23. The combination set out in claim 22 including a second switch in series with the first switch and the third switch when the latter is in its first position, and a sole-

noid when energized opening the second switch and interposed in series with all the switches when the first switch is in its second position and the third switch is in its first position.

24. A duplicating machine comprising a support for copy sheets, means for feeding sheets successively from the support through the machine, a rotatable drum for carrying a master for imprinting on the copy sheets passing through the machine, the feeding means including a gravity actuated pivoted follower adapted for engaging the copy sheets on the support, an electric motor for driving the drum and feeding means, a circuit for controlling the motor, a first and a third switch in said circuit, each switch having a normal first position and a second position, means controlled by the drum for moving the first switch to its second position, said follower having a pivoted arm biased to a home position, a starter arm having a normal retracted position in movement to which it is limited by engagement with the follower and operative in such position for engaging the pivoted arm and retaining said follower in raised position, and being operative on being depressed for releasing the follower and moving the third switch to its second position, said follower on being released from its uppermost position and descending therefrom being operative for retaining the third switch in its second position and when in its lowermost position enabling the starter arm to return and the third switch to assume its first position, said pivoted arm being capable of being cammed by the starter arm out of its said home position when the starter arm is in its said retracted position and the follower is raised to enable the follower to be so raised without actuating the starter arm and consequently actuating the third switch, the switches when in their first positions being in series with the motor and movement of the first switch to its second position stopping the motor, said third switch

5 10 15 20 25 30 35

when in its second position establishing a circuit to the motor.

25. A duplicating machine comprising, means for feeding copy sheets through the machine, means for imprinting on the sheets, an electric motor for driving the feeding means and imprinting means, circuit means including a switch movable between a first and a second position for controlling the motor, and means for automatically shutting off the machine in response to a predetermined condition of the machine in a cycle of operation thereof including latch means for retaining the switch in its second position, brake means for braking the motor, electromagnetic means in said circuit means, said switch being normally in its first position and being movable to its second position by the electromagnetic means, manually actuated means for causing the energization of the electromagnetic means and thus movement of said switch to its second position and operation of said latch means and brake means, the switch being arranged in the circuit means so that upon its being moved to its second position, it de-energizes the electromagnetic means, and thereby the electromagnetic means is energized only momentarily in the shutting off operation, and until the latch means becomes effective, the switch when moved to its second position is operative for interrupting the circuit for de-energizing the motor.
